GEORGE WILLIAM HEIMROD, OF HANOVER, GERMANY.

VAPOR RECTIFIER FOR HIGH-POTENTIAL CURRENTS.

1,366,452.

Specification of Letters Patent. Patented Jan. 25, 1921.

Application filed June 3, 1914. Serial No. 842,795.

To all whom it may concern:

Be it known that I, Dr. GEORGE WILLIAM HEIMROD, chemist, a citizen of the United States, residing at Hanover, Germany, No. 5 8 Bodenstedtstrasse, have invented certain new and useful Improvements in Vapor Rectifiers for High-Potential Currents, of which the following is a specification.

This invention relates broadly to vapor 10 electric devices and more particularly to vapor rectifiers for use on high potential circuits, such as employed for instance in operating Roentgen ray tubes.

Mercury rectifiers as in use at present 15 contain generally solid anodes of iron or graphite. Alternating currents of comparatively low potential are satisfactorily rectified by an apparatus of this sort. With currents of higher potential, however, difficulties invariably result inasmuch as the anode material is disintegrated under the influence of higher electric charges. Moreover these anode materials will liberate dissolved gases more or less readily, which deteriorates the vacuum of the rectifier. Since 20 complete rectification in mercury rectifiers depends on complete absence of gases in the discharge space these defects necessarily lead to discharges in the undesired direction, whereby complete rectification is made impossible. In case the rectifier is provided 25 with several anodes a discharge may take place between the anodes directly thus causing "arcing" or "striking-back." These defects increase with increase of potential and the practical limit of the rectifier now in use is generally considered to be at less than 10,000 volts. None of the anode materials now in use satisfies the demands to be made 30 upon them for complete rectification particularly under the influence of electrical discharges of high potential.

In the following it will be shown that 45 by replacement of the anode materials now in use by metals possessing qualities more fully in accord with the demands to be made upon such material, not only more complete rectification may be attained at voltages already employed, but that currents at potentials far above these present limits may be rectified completely.

Rectification in mercury rectifiers is the 50 result of the ease with which electrons are emitted from a hot mercury surface, as compared to the difficulty with which they meet in leaving the surface of a cold solid metal;

that is to say, while under the influence of cathodic charge negative electricity will flow readily from the hot cathode spot of a mercury cathode to a cold metallic anode, no 60 current can flow at even much higher potentials in the opposite direction. The higher the potential applied to the rectifier, the greater is the tendency for electrons to be emitted from the solid anode. To prevent this undesirable discharge it has been found necessary to free the mercury rectifier completely from gaseous impurities. With the anode material used so far this was impossible because the electrodes contained too 70 large quantities of gases which were given off slowly but continuously as soon as the anode material became disintegrated under the influence of electrical discharges.

In order to avoid these difficulties the 75 anode material should therefore have the following properties:

1. It must show little tendency toward amalgamation.

2. It must possess high heat and electrical 80 conductivity.

3. Even at relatively high temperatures, its vapor pressure must be low which corresponds to a high melting point.

4. It must resist the disintegrating effects 85 of electrical discharges.

5. It must have small tendency to dissolve gases or to retain them; that is, it must be possible to free the material readily from gaseous impurities.

6. Even at high cathodic potentials it 90 must not permit the emission of electrons. Since this seems to depend on the purity of the surface it must be possible to free the material from any layer of oxid, for instance by reduction.

Experiments of the applicant have shown that the metals, which combine the properties specified above for anode materials in mercury rectifiers, are tungsten, tantalum, 100 vanadium, molybdenum, uranium and niobium. They have also shown that these metals when used as anode material in mercury rectifiers either as such, or when alloyed with each other or with other metals 105 in proper proportion will permit a complete rectification, at any potential practically obtainable.

Obviously, it is not sufficient in order to 110 realize the conditions of this invention merely to employ suitable materials for the anodes of the rectifier such as above men-

tioned, but at the same time care must be taken that no other source of gas development is present in the discharge space of the rectifier. In this regard the invention is 5 distinguished from known forms of mercury lamps and rectifiers where a starting cathode covered with a layer of oxid of alkaline earths is provided within the discharge space; such starting device necessarily leading 10 to development of gas and therefore preventing the maintenance of the very high vacuum necessary for the rectification of currents of high tension, even if anodes of tungsten, etc., are used, as has been proposed 15 in connection with such lamps and rectifiers. As a further consequence of the necessity of avoiding the presence of even traces of ionizable gases within the rectifier space, all available means for eliminating 20 traces of gas which may adhere to the inner walls of the container vessel must be used in order to secure the effect aimed at. It is well known in the manufacture of incandescent electric lamps to free the inner 25 walls of the bulbs from adsorbed air by heating them to temperatures of say 350°, and more in extreme vacuum. It is important in connection with this invention to make use of this method also in the manufacture 30 of rectifiers in accordance therewith.

On account of the excellent valve action of mercury rectifiers equipped with these new anodes not only voltages far above those rectified so far can be completely rectified, but also far better efficiencies may be obtained 35 at normal potentials. This leads to entirely new and important applications of the rectifiers as for instance in Roentgen ray work. 40 Roentgen tubes require a unidirectional current of from 20,000 to 150,000 volts which could not be obtained satisfactorily before, except by a mechanical synchronous make and break apparatus such as the Snook converter. 45

With the improvement in the mercury rectifier herein described currents of potentials higher than those above mentioned may be rectified completely and automatically. It 50 is advantageous to provide the rectifier in this case with a second anode preferably of mercury from which by means of a direct current source a constant mercury arc is produced. The cathode spot of this arc will insure a regular and constant passage of the high tension current in the proper direction. 55

Another application of the new rectifier is suggested by the problem of generation of electric oscillations. In search of a solution 60 of this problem attention has often been called to the excellent qualities of mercury vapor and the rapidity with which mercury ions disappear. The attempts to utilize these properties for the production of high 65 frequency oscillations have failed on account

of the before mentioned inadequacies of the known types of mercury vapor valves. Under the influence of the relatively high current densities of condenser discharges the anode material became highly heated, disintegrated and evolved its gaseous impurities. With the replacement of such anode materials by the metals like tungsten, etc., these difficulties have been overcome. A mercury valve by itself or in conjunction 70 with spark gaps when properly connected to an oscillatory system may be used to generate oscillations at any frequency used in wireless telegraphy. By proper regulation of the energy charging the oscillatory 75 system, it is possible to produce discharges of almost any desired sequence up to continuous waves, since the mercury valve permits the discharge to take place in only one direction. The primary oscillatory system 80 is thus disconnected from the secondary system with which it is coupled and this permits not only a very firm coupling of the two systems but also a wide divergence of 85 the frequency of the two systems. 90

It is evident that these rectifiers may be used for the rectification of multiphase currents analogous to the methods now in use with the ordinary mercury rectifier. If necessary two or more may be used in parallel 95 or in series and the resulting wave crests may be smoothed out by proper self-induction. They may be used in any arrangement in which the rectifiers known at present have proved useful, but they may also 100 be employed for the rectification of currents at potentials at which the present rectifiers have failed completely. 105

A mercury rectifier in accordance with the invention is shown on the drawing. 110

The vessel of the rectifier is designated with the numeral 1, and contains a tungsten anode 2, a mercury cathode 3 and a further mercury electrode 4 adjacent the mercury cathode 3. The conductor 5 is for transmitting current from the source of electric power 6 and for connecting electrodes 3 and 4. A conductor 7 connects anode 2 and mercury cathode 3 and contains the direct current consumer 8. A coil 9, in the alternating current circuit 10 and the transformer coil 11, in connection with conductor 7 forms a source of alternating current to be rectified by the mercury rectifier 1. 115

The rectifier is started by producing a 120 mercury arc between electrodes 3 and 4. The ionized mercury arc forms the means to electrically bridge the space between mercury cathode 3 and tungsten anode 2 and at the same time to transform the alternating 125 current of circuit 10 into direct current which is consumed in direct current consumer 8 which may be a battery or some other device. It is essential for rectifying high tension currents that the space of the 130

rectifier 1 be under very high vacuum and that it does not contain any material which is adapted to give off gas under operative conditions.

5 What I claim is:

1. In a mercury rectifier, the combination of a tungsten anode actually freed from gases, a mercury cathode and a further electrode adjacent said mercury cathode and

10 freed from gases and gas evolving elements.

2. A mercury rectifier provided with anodes comprising as active material, metals capable of being freed and actually freed from gaseous and gas-evolving impurities,

15 inclosed within a receptacle free also from any other gas-evolving elements and likewise freed from any gas contained therein or

absorbed by its inner walls and by any elements inclosed thereby.

3. A mercury rectifier provided with 20 anodes comprising as active material tungsten actually freed from dissolved gases and inclosed within a receptacle free from any gas-evolving element and likewise freed from any gas contained therein or adsorbed 25 by its inner walls and by any elements inclosed thereby.

In testimony whereof I affix my signature in presence of two witnesses.

Dr. GEORGE WILLIAM HEIMROD.
